CLAIM

(57) The ornamental design for an electroblotting apparatus, as shown and described.

DESCRIPTION

FIG. 1 is a perspective view of an electroblotting apparatus; FIG. 2 is a right side view of the electroblotting apparatus of FIG. 1;

FIG. 3 is a left side view of the electroblotting apparatus of FIG. 1;

FIG. 4 is a front view of the electroblotting apparatus of FIG. 1;

FIG. 5 is a back view of the electroblotting apparatus of FIG. 1;

FIG. 6 is a top view of the electroblotting apparatus of FIG. 1; and,

FIG. 7 is a bottom view of the electroblotting apparatus of FIG. 1.

The broken lines illustrate portions of the electroblotting apparatus that form no part of the claimed design.
